UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

TANK-CAR CONSTRUCTION.

1,397,676.

Specification of Letters Patent.

Patented Nov. 22, 1921.

Application filed March 10, 1921. Serial No. 451,410.

To all whom it may concern:

Be it known that I, ARGYLE CAMPBELL, a citizen of the United States, residing at Chicago, in the county of Cook and State of Illinois, have invented a certain new and useful Improvement in Tank-Car Constructions, of which the following is a full, clear, concise, and exact description, reference being had to the accompanying drawings, forming a part of this specification.

This invention relates to improvements in tank car constructions.

One object of the invention is to provide a tank car construction having a low center of gravity to thereby minimize danger of tipping or derailment while the car is in motion.

Another object of the invention is to provide a tank car construction of unusual rigidity especially adapted to withstand not only all the usual shocks encountered in service but unusual and excessive shocks and strains without danger of tearing out any of the securing rivets or equivalent fastening means employed to anchor the shell or tank proper.

Another object of the invention is to provide a shell or tank proper construction which, *per se*, is effectively braced to withstand all tendency to twist under loads resulting from surging of the contents.

A specific object of the invention is to so arrange the riveting area directly between the underframe structure proper of the car and the bottom of the tank proper that the rivets are subject to lesser shearing stresses resulting from shocks tending to shift the tank proper relatively to the underframe, than obtains in present types of tank car constructions and furthermore to so minimize the shearing stresses on the rivets without at the same time increasing the tendency of the tank sheets to buckle.

Another specific object of the invention is to provide a bottom tank sheet construction which allows the center of gravity of the tank proper to be lowered, which tank sheet construction may be manufactured at comparatively small expense without the necessity of drawing of the metal in obtaining the desired formation.

Other objects of the invention will more clearly appear from the description and claims hereinafter following.

In the drawings forming a part of this

specification, Figure 1 is a central, longitudinal, vertical section of a tank car construction showing my improvements in connection therewith, only a portion of the tank car being illustrated. Fig. 2 is a broken side elevational view of the tank car illustrated in Fig. 1. Fig. 3 is a part horizontal sectional view, part top plan of one of the end underframe arrangements with the tank proper removed. The scale of Fig. 3 is smaller than that of Figs. 1 and 2 in order to better accommodate the view on the sheet. And Figs. 4, 5 and 6 are broken vertical transverse sectional views corresponding respectively to the section lines 4—4, 5—5 and 6—6 of Fig. 1.

In the drawings, I have illustrated only so much of the complete car as is necessary to an understanding of my improvement. The drawings illustrate one end of the tank car from the end sill to a point inwardly of the underframe construction employed at each end of the car, it being understood that the arrangement shown in the drawings is duplicated at both ends of the tank car and that, intermediate the end portions, the tank is of the usual cylindrical form and provided with the customary filling dome, discharge pipe and accessories.

In said drawings, the shell or tank proper is shown of cylindrical form substantially from end to end, except as hereinafter noted and, in forming the tank proper, I preferably employ a longitudinally extending bottom tank sheet A extending from end to end of the tank proper; a plurality of circular band sheets B—B riveted at their ends to the edges of the bottom tank sheet A as indicated at 10—10, and convex ends C.

As shown, at each end of the car, I employ an under-frame arrangement which consists of a combined draft sill and center sill member D; a built-up bolster E; short channel side sills F—F; an end sill G; and diagonally extending struts H—H, the latter preferably being in the form of channels with their flanges flattened at the ends in order to adapt them for riveting to the bolster and end and side sills. The built-up bolster E, as shown, includes a center filler casting 11 disposed within the member D, and pressed diaphragms 12—12 conformed to the tank on each side of the filler casting, top and bottom tie plates 13—13 being also used.

The combined draft sill and center sill 110

member D is preferably in the form of a sheet metal pressing of substantially inverted U form and having side webs 14-14 and a top connecting web 15. Along the bottom edges of the webs 14, outturned flanges 16-16 are formed to increase the strength as will be understood. Said member D extends from the end sill G through the bolster E and to a point inside of the bolster a distance slightly less than the distance from the center of the bolster to the end sill and to a point as indicated at 17 in Figs. 1 and 2. From the end sill to the bolster, the cross section of the member D remains constant at all points therealong but on the inner side of the bolster at a point beginning at 18 as best shown in Figs. 1 and 2, the height of the member D is gradually decreased so that the top connecting web 15 thereof is sloped downwardly and inwardly as indicated at 15^a in Figs. 1 and 2, said sloping portion 15^a being utilized as the direct riveting area for the tank proper, as hereinafter explained. Stop lugs for the draft gear of any desirable form may be secured to the inner sides of the webs 14 as indicated at 19-19. Braces and tie plates may also be employed to strengthen the member D inwardly of the bolster as indicated at 20-20. As clearly indicated in Figs. 5 and 6, the lower portions of the webs 14 of the member D are extended in planes below the lowermost part of the tank although it is evident that the lowermost points in the bottom of the tank are well below the center line of the draft rigging.

The bottom sheet A of my improved tank car construction is of special form and manufacture in order to provide for the lowering of the center of the tank. Said bottom sheet A is cut to the desired length and width and first bent into true cylindrical or convex form throughout its length as is now done with corresponding bottom sheets of tanks which are truly cylindrical at every point therein. It will thus be seen that, so far as the initial steps in the manufacture of my bottom plate A are concerned, the same machines now in use may be utilized. The bottom sheet A, initially cut and bent as just described, is next subjected to a press which indents it or bends it inwardly of the tank to the peculiar form shown and it will be noted that said plate A, as shown, has flat portions extending centrally longitudinally thereof as indicated at 115-115^a adapted to rest upon and conform to the portions 15-15^a of the top web of the member D. On each side of the central portions 115-115^a, the plate A is made convex on its inner side as indicated at 21-21, said portions 21 merging with the initially formed cylindrical side portions 22-22 along lines indicated at 23-23. Each line of coalescence 23 is straight and extends horizontally

from the end of the tank to a point inside of the bolster as indicated at 24 opposite the point 18 and then extends downwardly and gradually inwardly toward the center line of the tank sheet A until the contour of the sheet A assumes its true cylindrical form intermediate the underframe constructions at each end of the car. In indenting the sheet A as just described, I so form it that the length of any line of section of said plate A between the lines of coalescence 23, at any point along the sheet A, equals the length of any arcuate section between corresponding points as obtained in the sheet A initially formed truly cylindrical throughout so that the sheet A as ultimately formed does not involve any drawing of the metal but merely simple bending. This I consider of importance inasmuch as the cost of manufacture of the specially shaped bottom sheet A is reduced to a minimum and at the same time its initial strength retained without danger of lines of weakness being developed during the process of manufacture.

As will be understood from the foregoing, the sloping section 115^a of the bottom sheet A is riveted to the section 15^a and hence the rivets themselves will extend at an angle to the horizontal. With this arrangement, all ordinary buffing and pulling shocks which are transmitted in horizontal lines to the underframe, and which ordinarily tend to shift the tank with respect to the underframe, will have their shearing effect on the rivets directly uniting the underframe and tank reduced. This results from the inclined engagement between the underframe member D and the bottom of the tank which causes the horizontally transmitted forces to be partly converted into components extending perpendicular to the sloping planes of the sections 15^a and 115^a.

To further assist in anchoring the tank proper to the underframe, I employ two longitudinally extending plates 25-25, one on each side of the center sill arrangement and located inwardly of the bolster. Each of said plates 25 has the main portion thereof curved to conform to the periphery of the tank and is riveted to the bottom sheet A by lines of rivets 26-26 which follow approximately the adjacent portions of the lines of coalescence 23 hereinbefore referred to. Along their inner edges, the plates 25 are formed with vertically downwardly extended flanges 27 which are riveted to the corresponding portions of the webs 14 of the member D as best shown in Figs. 5 and 6. The combination of the indented portions of the plate A, oppositely curved plates 25 and member D forms an unusually rigid girder-like construction having top and bottom chords and struts. This structural formation is especially effective in preventing tendency of the tank

proper to twist or warp under loads imposed by the surging of the contents of the tank proper.

The tank proper is additionally braced 5 and connected to the underframe construction by means of vertically extending plates 28—28 at each end of the bolster, said plates 28 being riveted at their bottom edges to the side sills and at their top edges to the 10 tank. Partial cradle seats are provided for the tank at the bolster on each side of the center by means of blocks 29 and interposed wood fillers 30—30.

From the preceding description, it will 15 be seen that the center of gravity of the contents of the tank is appreciably lowered as compared with tanks of same diameter which are not dropped below the tops of the center sills of the car and this result is 20 accomplished without any material increase in cost of manufacture of the tank proper and without any material loss of capacity.

In the drawings I have illustrated the center sills as terminating a few feet inwardly of each bolster but it will still be 25 within the purview of my invention to make the center sills continuous from bolster to bolster. With the construction shown, I deem it unnecessary to make the center sills 30 continuous for the reason that my tank proper is united to the underframe at each end of the car in no less than five different places, two of these being between the side plates 28 and the tank; two of them be- 35 tween the anchor plates 25 and the tank; and the last between the engaging sloping portions of the member D and tank bottom. In this connection, it will also be observed that the points of anchorage between the 40 tank and underframe at each end of the car are comparatively concentrated as regards the length of the tank and the lines of anchorage arranged laterally opposite each other so that the main portion of the tank, 45 between the points of anchorage, is adapted to expand and contract freely without danger of rupturing any of the rivets and, similarly, the ends of the tank between the bol- 50 sters and end sills are also free to expand and contract without in any wise affecting the securing rivets. As indicated, the pro- 55 jecting ends of the tank are free to expand and contract relatively to the underframe but nevertheless the load of said tank ends is directly supported by the member D.

I have herein shown and described what I now consider the preferred manner of carrying out the invention but the same is merely illustrative and I contemplate all 60 changes and modifications that come within the scope of the claims appended hereto.

I claim:

1. In a tank car construction, the combination with the underframe including a bolster and draft sills at each end of the car; of 65

a tank proper of generally cylindrical form throughout and the bottom of which, between bolsters, extends below the tops of the bolsters, said tank at each end having a bottom sheet extending over the draft sills and 70 bolsters to points spaced inwardly of and away from the bolster, said sheet being bent inwardly of the tank and secured at its edges outside of the draft sills to other cylindrically curved tank sheets, the length of 75 any line of section of said bottom sheet at any point therealong taken transverse to the tank equaling the length of any similarly taken section of a sheet outwardly curved throughout to conform to the periphery of 80 the tank and adapted to be secured to said other tank sheets at corresponding points, said bottom sheet merging into cylindrical form inwardly of the bolster.

2. In a tank car construction, the combination with the draft sills and bolsters; of a tank of generally cylindrical form throughout, the bottom of said tank, at each end where extended over the bolster and draft sills and also inwardly of the bolsters, being 90 indented, the length of the perimeter of said tank at all points along said indented ends equaling the perimeter of an undented true cylindrical tank of the same diameter whereby said indented bottom portions of the tank 95 may be made of sheets of original cylindrical form corresponding to the diameter of the tank and then indented without drawing of the metal.

3. In a tank car construction, the combination with the draft sills and bolsters; of a tank proper of generally cylindrical form throughout, said tank proper being formed of a longitudinally extending continuous bottom sheet, end sheets and circularly ex- 100 tending band sheets united at their free edges to said bottom sheet, said bottom sheet, intermediate the bolsters, being of curved cylindrical form conforming to the diameter of the tank and inwardly indented 105 at each end over the bolsters and draft sills, the lengths of all lines of cross section of said bottom sheet taken transverse to the tank proper being equal whereby said bottom sheet may be initially formed of the 110 same curvature throughout its length and then indented at its ends by bending.

4. In a tank car construction, the combination with the underframe including a bolster and draft sills at each end of the car; of 115 a tank proper of generally cylindrical form throughout, the bottom of the tank proper being extended below the tops of the bolsters between the latter and including a continuous bottom sheet, said tank at each end 120 having said bottom sheet extended over the bolster and draft sills and inwardly indented, said indented portions resting upon the bolster and draft sills to the end of the tank, said bottom sheet on each side of the draft 125 130

sills being extended downwardly below the tops of the draft sills both outwardly and inwardly of each bolster.

5. In a tank car construction, the combination with the underframe including, at each end of the car, a bolster, draft sills, and center sills inwardly of the bolster, the tops of said center sills sloping downwardly and inwardly toward the center of the car; of a 10 tank proper, the bottom of which intermediate the bolsters, is dropped down below the tops of the bolsters, the end portions of the bottom of the tank proper being indented inwardly of the tank and conforming to the 15 lines of the tops of the draft sills and said sloping tops of the center sills, the bottom of the tank being secured to said center sills along said sloping tops thereof.

6. In a tank car construction, the combination with the underframe which includes, 20 at each end of the car, a bolster, draft sills, and center sills inwardly of the bolster, the tops of the latter sloping downwardly and inwardly toward the center of the car; of a 25 tank proper of generally cylindrical form throughout, the bottom of said tank, at each end where extended over said center sills, bolster and draft sills, being indented and conformed to the tops of the draft sills and 30 sloping tops of the center sills and united to the latter, the length of any line of section of said tank at all points along said indented ends of the tank equaling the length of the perimeter of an undented cylindrical tank 35 of same diameter.

7. In a tank car construction, the combination with the underframe including, at each end of the car, draft sills, bolster and center sills inwardly of the bolster, the latter 40 having the tops thereof sloped downwardly and inwardly from the bolster; of a tank proper, said tank proper having a portion of the bottom thereof sloped to conform to and rest upon said sloping tops of the center sills and riveted to the latter whereby 45 said rivets are extended at an angle to the usual lines of horizontally imposed shock forces and the shearing stresses thereon reduced.

50 8. In a tank car construction, the combination with draft sills, bolster and center sills at each end of the car, the center sills being united at their tops by a plate, the latter being sloped downwardly and inwardly from the bolster and providing a flat 55 riveting area inclined to the center line of draft; of a tank proper having the bottom thereof, intermediate the bolsters, dropped down below the center line of draft, the bottom 60 of said tank having flat sloping sections resting upon and riveted to said sloping top plates of the center sills.

9. In a tank car construction, the combination with a combined draft and center sill 65 member, said member being of substantially

inverted U cross section and including side webs and top connecting web, the latter, inwardly of the bolster line sloping downwardly and providing a riveting area; of a tank proper of generally cylindrical form 70 throughout, the bottom of said tank being dropped below the center line of draft at points intermediate the bolsters, the bottom of said tank having a flat section resting upon and riveted to said sloping web portion. 75

10. In a tank car construction, the combination with the underframe including, at each end of the car, draft sills, bolster and center sills inwardly of the bolster, the latter having the tops thereof sloped downwardly and inwardly from the bolster; of a tank proper, said tank proper having a portion of the bottom thereof sloped to conform to and rest upon said sloping tops of the center sills and riveted to the latter whereby 80 said rivets are extended at an angle to the usual lines of horizontally imposed shock forces and the shearing stresses thereon reduced; and anchor plates each united along one edge to the bottom of the tank outside of 85 the center sill and along its other edge to the center sill, said anchor plates being laterally opposite said sloping portions of the center sill. 90

11. In a tank car construction, the combination with a tank proper of generally cylindrical form and including a longitudinally extending bottom sheet, said bottom sheet, centrally of the tank proper, being curved to conform to the cylindrical periphery of the tank proper and at each end being inwardly indented, each indented portion including a horizontally extending flat section and a sloping section inwardly thereof, the length of all lines of cross section of said plate taken transverse of the tank being equal; of a bolster at each end of the car; draft sills at each end of the car and upon which said flat sections of the indented portions of the bottom sheet rest; and center 100 sills intermediate the bolsters sloped downwardly and inwardly from the bolsters and having top plates engaging with and riveted to said sloping sections of the indented ends 105 of the tank proper. 110

12. In a tank car construction, the combination with a tank proper of generally cylindrical form and including a longitudinally extending bottom sheet, said bottom sheet, centrally of the tank proper, being curved to conform to the cylindrical periphery of the tank proper and at each end being inwardly indented, each indented portion including a horizontally extending flat section and a sloping section inwardly thereof, the length of all lines of cross section of said plate taken transverse of the tank being equal; of a bolster at each end of the car; draft sills at each end of the car and upon which said flat sections of the in- 115 120 125 130 135

dented portions of the bottom sheet rest; center sills intermediate the bolsters sloped downwardly and inwardly from the bolsters and having top plates engaging with and riveted to said sloping sections of the indented ends of the tank proper; and anchor plates disposed inwardly of the bolsters and on each side of the center sills, each anchor plate being secured along one edge to the bottom sheet of the tank proper and along its other edge to a center sill, said anchor plates being disposed laterally opposite said sloping portions of the center sills.

13. In a tank car, the combination with the under-frame construction including draft sills, bolsters, and center sills inwardly of the bolsters in line with the draft sills; of a tank proper of substantially cylindrical form; and means for securing said tank proper to said center sills at points both above and below the center line of draft.

14. In a tank car, the combination with the underframe construction including draft and center sills; of a tank proper of generally cylindrical form indented at its ends to fit over the draft sills; and anchor plates of curved form corresponding to the curvature of the bottom of the tank proper, said anchor plates being rigidly secured to the tank proper at points above the center line of draft and to the underframe construction at points below the center line of draft.

15. In a tank car, the combination with the underframe construction including draft and center sills; of a tank proper of generally cylindrical form; and anchor plates of convex cylindrical form secured to the tank proper at points above the center line of draft and to the draft sills inside of the

bolster at points below the center line of draft.

16. In a tank car, the combination with the underframe construction including a bolster, draft and center sills; of a tank of substantially cylindrical form throughout with the bottom indented at the ends thereof to adapt the tank to fit over the bolster and draft sills and rest thereon; means for securing the tank proper to the center sills direct inwardly of the bolster; and supplemental anchor plates secured to the tank proper and to the center sills, the points of attachment of said anchor plates to the center sills being below the center line of the draft sills. 55

17. In a tank car, the combination with the underframe construction including, a body bolster, draft sills and center sills; of a tank proper; means securing the bottom of said tank directly to the center sills; anchor plates on opposite sides of the center sills secured to the tank and to the center sills at points spaced from the direct connections between the tank and center sills; and additional side anchor plates secured to the tank proper at points spaced from and above the points of connection between the first named anchor plates and the tank, said side anchor plates being also secured to the underframe construction. 70

In witness that I claim the foregoing, I have hereunto subscribed my name this 21st day of February, A. D. 1921.

ARGYLE CAMPBELL.
